UNITED STATES PATENT OFFICE.

FRANK VESCUSO, OF PROVIDENCE, RHODE ISLAND.

RECEPTACLE FOR HOLDING MILK BOTTLES.

Application filed August 27, 1921. Serial No. 495,858.

To all whom it may concern:

Be it known that I, FRANK VESCUSO, a citizen of the United States, residing at Providence, in the county of Providence and 5 State of Rhode Island, have invented certain new and useful Improvements in a Receptacle for Holding Milk Bottles, of which the following is a specification.

This invention relates to a compound receptacle adapted more particularly for use 10 as a milk bottle holder; and the object of this invention is to provide such a receptacle with an upper and a lower section, the upper section being adapted to be withdrawn 15 from over the lower section to receive the milk bottles or other articles to be deposited therein, after which it may be returned to normal over the lower section, and a false bottom member is provided in the upper 20 section adapted to be withdrawn to permit the contents to drop from the upper into the lower section when the two are in position to register one above the other.

A further object of this invention is to 25 provide cushioning means in the lower section onto which the articles may fall to prevent their breaking; means being also provided for locking the movable section in closed position when desired.

With these and other objects in view, the 30 invention consists of certain novel features of construction, as will be more fully described, and particularly pointed out in the appended claims.

In the accompanying drawings:

Figure 1 is a side elevation in section showing the compound receptacle with the upper portion thereof drawn out and filled with milk bottles.

Figure 2 shows the upper section as having been pushed back to normal position over the lower section, the false bottom member withdrawn and the milk bottles dropped into the lower section.

Figure 3 is an end elevation of the compound receptacle.

Figure 4 is an enlarged end view illustrating the construction by which the upper section is slidably mounted upon the rolled edge of the lower section; also showing the edge bearing for the false bottom member.

Figure 5 is a top view showing one of the compartments in one of the sections of the receptacle with the partitions riveted to its side walls.

Figure 6 is a rear end view showing a

portion of both the upper and lower sections of the receptacle; and also the button or locking latch by which the upper section may be locked in its closed position. 60

With reference to the drawings, 10 designates the side of a house into which my improved compound receptacle is built, the lower section 11 of this receptacle is preferably located entirely within the house and 65 is made immovable and of a height a little greater than that of a milk bottle, and this section of the receptacle is preferably divided into four compartments for the reception of as many different bottles, but 70 any number of compartments may be provided, partitions 12 being placed between the different compartments. In the bottom of each compartment is shown a leaf-spring 75 13 onto which the bottle may fall from the upper compartment to serve as a cushion and so prevent breaking the bottle from the shock of falling.

The different sections of my improved receptacle are both constructed preferably of 80 metal, such as galvanized iron or the like, and the upper edge of the lower receptacle, as shown at 14 in Figure 4, is preferably rolled over outwardly over a wire core 15, providing a suitable bearing on which the 85 upper member 16 of the receptacle may slide. The lower edge of this upper section being curved outwardly and around the enlarged upper edge of the lower section, connecting the two together and permitting the 90 upper to slide freely upon the lower section while moving in and out over the same.

The upper section 16 is like the lower section provided with a plurality of spaced apart partitions 17 which register with the partitions 12 of the lower section. A handle 18 is formed on the front of this upper section to be engaged by the hand of the milkman to be drawn out through the opening 19 in the side of the building until it brings 100 up against the stop 20 at its inner end, thereby exposing the four compartments 21 into which as many milk bottles 22 may be deposited.

This upper section is then pushed back 105 over the lower section, as illustrated in Figure 2, when the false bottom member 23 may be withdrawn, as illustrated in Figure 2, permitting the bottles to drop from the upper section into the lower section, upon the cushioning springs 13 therein, after which 110 this false bottom member is pressed back

into position and its notched portion 24 is engaged by the spring detent 25 to hold it in closed position to move with the upper section of the receptacle.

5 As will be seen, no unauthorized person can now obtain the milk bottles from the upper section of the receptacle even though they should withdraw it from its closed position.

10 When the housewife wishes to obtain these bottles it is only necessary for her to press the upper section 16 outward from the inside of the house, thus exposing the bottles in the lower section which she can readily 15 obtain therefrom, and after using the contents thereof the empty bottles may be placed in the compartments of the upper section so that when the milkman withdraws this section in the morning he may 20 first take therefrom the empty bottles and replace them with full ones.

In some instances during the day it may be desired to lock the upper section in its closed or normal position, in which case I 25 have provided a button 26 on the rear of the upper section which, as illustrated in Figure 6, may be turned from the position shown in full lines, to the vertical position illustrated in dotted lines, in which case the 30 upper section is securely locked to the lower section against being withdrawn by unauthorized persons. This lock may be moved to unlocked position at night so as to permit the milkman to operate the receptacle 35 in the morning.

Although the particular construction illustrated is designed especially for the reception of milk bottles, I do not wish to be restricted to the use of a receptacle for 40 this purpose only, as a receptacle constructed similar to that shown and described may be used for any purpose for which it may be adapted. The device is extremely simple and practical in construction and effective 45 in its operation, and by its use the theft of filled milk bottles is effectually prevented by persons on the outside of the house.

The foregoing description is directed solely toward the construction illustrated, 50 but I desire it to be understood that I reserve the privilege of resorting to all the mechanical changes to which the device is susceptible, the invention being defined and limited only by the terms of the appended 55 claims.

I claim:

1. A compound receptacle comprising upper and lower sections of substantially the

same capacity, the upper section being movable relatively to the lower section and both 60 having a plurality of compartments registering with each other when the upper section is in normal position, and a false bottom member in the upper section adapted to be withdrawn to drop the contents of 65 the upper into the lower section when desired.

2. A compound receptacle comprising upper and lower substantially duplicate sections, the upper being longitudinally movable from over the lower to receive the articles to be deposited therein, a false bottom member in the upper section adapted to be withdrawn to drop the contents of the upper into the lower section when the two 75 are positioned to register, and cushioning means in the lower section into which the articles may fall to prevent breakage.

3. A compound receptacle comprising upper and lower sections each substantially 80 divided into compartments, the upper being adapted to be withdrawn from over the lower to receive the articles to be deposited therein, a false bottom member in the upper section and adapted to be withdrawn to 85 drop the contents of the upper compartments into corresponding compartments of the lower section when the two are positioned to register, and means for locking the movable section in closed position when desired. 90

4. A compound receptacle comprising upper and lower sections of substantially the same capacity, the upper being adapted to slide upon the upper edge of the lower section and to be withdrawn therefrom to receive the articles to be deposited therein, a false bottom member mounted to slide with the upper section and adapted to be withdrawn to drop the contents of the upper into the lower section when the two are positioned to register, and a detent for locking said false bottom to said upper section. 95

5. A compound receptacle comprising upper and lower substantially duplicate subdivided sections, one being movable relatively to the other, said subdivisions of the sections forming compartments registering when the sections are in normal positions, a removable bottom in the upper section whereby the contents in the compartments 100 of the upper section are permitted to be deposited into their corresponding registering compartments in the lower section. 110

In testimony whereof I affix my signature.

FRANK VESCUSO.
